(57) **CLAIM**

The ornamental design for a shoe, as shown and described.

DESCRIPTION

FIG. 1 is a first perspective view of a shoe showing my new design;

FIG. 2 is a second perspective view thereof;

FIG. 3 is a right side view thereof;

FIG. 4 is a left side view thereof

FIG. 5 is a back view thereof;

FIG. 6 is a front view thereof;

FIG. 7 is a top view thereof;

FIG. 8 is a bottom view thereof; and,

FIG. 9 is an enlarged view of the selected portion "9" in FIG. 1.

The broken lines shown in the drawings depict portions of the shoe that form no part of the claimed design. The short broken lines on top of claimed portions of the shoe upper depict stitching, which form no part of the claimed design.

1 Claim, 9 Drawing Sheets
